STOKER PIPE

Harold T. Blum, Glenmont, Ohio, assignor to
Eriar Hill Corporation, Millersburg, Ohio, a corporation of Ohio

Application January 10, 1939, Serial No. 250,220

3 Claims. (Cl. 131—181)

The present invention relates to smoking pipe structures and more especially to pipe structures providing an arrangement for producing a cool, dry smoke.

5 The principal object of the present invention is to provide a pipe structure and arrangement thereof which will deliver to the user a cool, dry and tar-free smoke.

A further object of the present invention is to 10 provide a pipe structure and arrangement thereof which is economical to manufacture and yet is capable of being readily cleansed, while at the same time, capable of providing a cool, dry smoke to the user thereof.

15 And it is an equally important object of the present invention to provide a smoking pipe that will not become caked nor cause a loss in the tobacco used and yet will at the same time provide a smoke which is cool and has had objectionable heavy oils, tars and water-vapors condensed therefrom and which condensed liquids are prevented from reaching a user thereof.

20 Other objects of the present invention will be partly obvious and in part pointed out in the following detailed description of the accompanying drawing.

In the drawing:

Figure 1 is a side cross-sectional view of the pipe structure embodying the present invention.

30 Figure 2 is an enlarged detailed side cross-sectional view of a part of the pipe structure embodying the present invention.

Figure 3 is a cross-sectional view taken on line 3—3 of Figure 2.

35 Figure 4 is a perspective view of the tobacco reservoir forming part of the pipe structure, and

Figure 5 is a perspective view of the baffles and their connection to one another as used with the pipe structure.

40 Referring now more particularly to the accompanying drawing wherein like reference characters designate like members, numeral 1 designates a tubular shaped member having a substantially L-shaped configuration and which member is to be formed from a lightweight metal or a plastic. The extended arm 3 of said member 1 has detachably connected by means of threads at 28 a mouthpiece 5 of the usual construction and which has a bore 27 extending axially thereof. Arm 2 of member 1, which as shown, is formed to simulate a pipe bowl, extends somewhat at right angles from arm 3. The end of arm or portion 2 of member 1 is stepped, having a flange 9 extending perpendicular therefrom and which flange 9 has an extending wall

10 positioned perpendicularly from the end thereof. Said wall 10 is, as shown, threaded upon its periphery.

A pipe tobacco reservoir 14 is formed from a tubular piece of metal having a wall 12 and a flange 11 extending perpendicular from one end of said wall 12. Wall 12 has formed therethrough a series of openings 13 at a point near the flanged edge 11. Slidably mounted for longitudinal movement within the tobacco reservoir 14 and extending thereacross is a circular concave plate 15 formed or stamped from a metal. Formed with said plate 15 at the central point thereof is an extending portion 16 having a threaded bore formed axially thereof. Said plate 15 has a threaded shaft 17 extending through the threaded bore of portion 16 and shaft 17 extends through the bore of a stop and support member 20 to a point outside of member 1 where it terminates with a knurled head 19 mounted thereon. Said member 1 has an opening 21 formed therethrough in which is mounted said stop and support member 20, which member 20 has portions thereof bent to completely enclose said opening 21. Said shaft 17 has a radially extending projection 18 formed upon the periphery thereof which is received in a recess extending from the bore of said member 20, thereby preventing a sliding movement of said shaft 17 longitudinally of the bore of member 20.

30 A ring 4 formed preferably of a heat insulating material such as a plastic or wood and having a tapered bore 6 extending centrally thereof has its outer walls shaped to cooperate with the walls of portion 2 to complete therewith the appearance of a smoking pipe bowl. Said ring 4 further has bore 6 stepped, forming a longitudinally extending threaded wall 7 connected to said bore 6 by a step 8.

35 A series of baffles 24 and 25 formed from a heat conductive material and carried by a bar 23 in spaced relationship to one another and which baffles have a radius equivalent to the interior wall surface of arm 3 and which are in the form of a substantially semi-circular disc are inserted 40 through the open end of arm 3 before the insertion therein of mouthpiece 5. These baffles are shaped and positioned relative to bar 23 in such a manner that they will frictionally engage with the interior wall surface of arm 3 to form a series 45 of interconnected compartments as shown in Figures 1 and 2. Bar 23 connecting the baffles 24 and 25 is formed of a flexible metallic material and where it is desirable to form arm 3 having a curved shape, the baffles may be readily 50

inserted within the arm 3 and the bar 23 will, of its own accord, bend to agree with the curve of arm 3. Therefore, the arrangement of baffles as disclosed in Figure 5 may be readily used with either pipe constructions having a straight or curved stem portion.

Metallic and tubular member 1 has the tobacco reservoir 14 mounted within portion 2 by placing flange 11 upon the edge of wall 10. The insulated ring 4 is then screwed onto wall 10 and the connecting portion 8 of ring 4 will be caused to bear against a heat insulating disc 31 and thereby retain said flange 11 against wall 10, and at the same time, spacing wall 12 of reservoir 14 from said wall 10. Ring 4 is further insulated from portion 2 by a disc 30 of heat insulating material mounted on the step of portion 2. Further, bore 6 which has its larger diameter equivalent to the diameter of the interior of reservoir 14 will be positioned in line therewith, with bore 6 gradually narrowing as it tapers upwardly.

With tobacco placed in reservoir 14, the user of a pipe according to the construction herein described may, upon applying a flame to the tobacco and drawing through mouthpiece 5, cause the ignition of the tobacco, inasmuch as the suction applied through bore 27 of mouthpiece 5 will draw air inwardly through bore 6, through the tobacco and then through openings 13 to within the interior of the tubular member 1 and past the baffles 25 and 24. The smoke drawn from the burning tobacco will obviously pass through only a small portion of the tobacco before it enters through openings 13 to the large and spacious interior of member 1. As the tobacco is burnt and consumed, the user of the pipe will, by turning knurled knob 19 cause plate 15 to be progressively advanced upwardly due to the threaded engagement of rod 17 with the bore of said plate 15. Plate 15, being in frictional engagement with the interior of wall 12 or where found desirable in a guide and slot arrangement, not shown, with the interior of said wall 12, will be prevented from rotating and upon the turning of shaft 17 will advance upwardly, forcing the tobacco from reservoir 14 to within bore 6. Bore 6, being tapered, will compress the tobacco forced thereinto and will therefore provide a uniform and continuously burning tobacco. As the burnt tobacco will, by this arrangement, remain within the bore 6, the ashes therefrom can readily be shaken outwardly without interfering with the burning of the remaining tobacco, due to the remaining tobacco being in its compressed condition, whereas, of course, the ashes are in a relatively loose state.

Plate 15, which has an extending portion 16 located centrally thereof, will, upon being advanced to the lower portion of reservoir 14, be automatically stopped by the portion 16 contacting an extended portion 22 of member 20.

The burning of the tobacco will always take place within the bore 6 and the heat therefrom will be confined within the insulated ring 4 and, therefore, portion 2 will remain cool due to the interposition between portion 2 and the bore 6 of the heat insulating discs 30 and 31. The walls 12 of reservoir 14 will contain tobacco or, upon the upward movement of plate 15, will be gradually emptied but will be protected by plate 15 and the tobacco thereon from the heat of the burning tobacco within bore 6. Therefore, the space 29 between wall 12 and the tubular member 1 will remain cool and this is further aided by constructing the member 1 of a lightweight metal

which will readily conduct heat therefrom. By maintaining space 29 in a cool condition, the objectionable heavy oils, tars and water-vapors coming from openings 13 will be caused to condense and drop to the bottom of said member 1. Baffles 25 and 24 prevent these condensed liquids from reaching the mouthpiece 5 and, further, aid in the cooling of the smoke as well as further condensing any remaining liquids before the smoke reaches opening 27. The baffles 25 and 24, being in close contact with arm 3, will conduct heat from the smoke to the arm 3 which, being of a lightweight material, will readily conduct the heat to the atmosphere whereby the smoke as it passes over ends 26 of each of the baffles will be gradually cooled before reaching said opening 27.

Space 29 has sufficient volume to hold smoke coming through openings 13 to permit the smoke therein to cool between puffs by the smoker. As plate 15 is gradually moved upward, the volume of space 29 is increased and, therefore, as the area within bore 6 becomes hotter with the continued burning of the tobacco therein and with the resulting raising of temperature of the smoke from openings 13, the volume of space 29 will be increased to accommodate more smoke and, therefore, permit the same to remain longer in order to be sufficiently cooled to condense the liquids therein before reaching the smoker.

By removing ring 4, tobacco reservoir 14 may be readily withdrawn from within arm 2 and also by unscrewing mouthpiece 5, the baffles 24 and 25 can be removed from arm 3. Therefore, by two simple operations, all of the members forming the pipe construction can be removed for cleaning without leaving any unaccessible points or hard to get at places which would prevent the removal of the condensed liquids therefrom.

My invention is capable of considerable modification but such modifications as come within the scope of the appended claims, I deem to be within the spirit of my invention.

I claim:

1. A smoking pipe comprising an outer bowl of heat-conducting material, a stem having the bore thereof connected to the bore of said bowl, an inner bowl spaced from said outer bowl, means maintaining said inner bowl in spaced relationship to said outer bowl and closing the space between the upper ends of said bowls, said inner bowl including a plate slidably mounted longitudinally thereof, perforations formed through the wall of said inner bowl and positioned substantially at the upper end of said outer bowl, means formed of heat-insulating material having an opening formed therethrough positioned above the top ends of said inner and outer bowls, said insulating means being of such thickness in a direction parallel to the axis of said inner bowl that the opening formed through said insulating means will constitute substantially the entire tobacco burning area during the smoking of the pipe and manually operable means connected to said plate and adapted to shift tobacco supported on said plate upwardly for maintaining the tobacco combustion area within the opening formed through said insulating means.

2. A smoking pipe comprising an outer bowl of a heat-conducting material, a stem having the bore thereof connected to the bore of said bowl, an inner bowl of heat-conducting material spaced from said outer bowl, said inner bowl consisting of a tube having an outwardly extending flange at the upper end thereof and a bottom slidably

mounted longitudinally of said tube, perforations formed through the wall of said tube adjacent said flange and positioned substantially at the upper end of said outer bowl, a heat-insulating 5 ring positioned above said flange and the top of said outer bowl and maintaining said tube and said outer bowl in assembled relationship, said insulating ring being of such thickness in a direction parallel to the axis of said tube that the 10 space within said ring will constitute substantially the entire tobacco burning area during the smoking of the pipe, and manually operable means mounted through said outer bowl connected to said bottom and adapted to shift tobacco 15 supported on said bottom upwardly for maintaining the tobacco combustion area within the space formed by said ring. 3. A smoking pipe comprising an outer bowl of heat-conducting material, a stem having the bore thereof connected to the bore of said bowl, an 20 inner bowl of heat-conducting material spaced from said outer bowl, said inner bowl consisting of a tube having an outwardly extending flange at the upper end thereof and a bottom slidably mounted longitudinally of said tube, perforations formed through the tube wall adjacent to said flange and positioned substantially at the upper 5 end of said outer bowl, a heat-insulating ring positioned above said flange and the top of said outer bowl and maintaining said tube and said outer bowl in assembled relationship, heat-insulating washers interpositioned between said 10 insulating ring and the upper ends of said outer bowl and said inner bowl, said insulating ring being of a thickness in a direction parallel to the axis of said tube so that the bore thereof will constitute substantially the entire tobacco burning area during the smoking of the pipe, and manually operable means connected to said bottom and adapted to shift tobacco supported on said bottom upwardly for maintaining the tobacco combustion area within the space formed 15 by said ring.

HAROLD T. BLUM.
